(57) **CLAIM**

We claim the ornamental design for a face plate for a radio telephone, or similar articles substantially as shown.

DESCRIPTION

FIG. 1 is a perspective view of a face plate for a radio telephone or similar articles.

FIG. 2 is a front orthogonal view according FIG. 1.

FIG. 3 is a back orthogonal view according FIG. 1.

FIG. 4 is a first side orthogonal view according FIG. 1.

FIG. 5 is a second side orthogonal view according FIG. 1.

FIG. 6 is a top orthogonal view according FIG. 1; and,

FIG. 7 is a bottom orthogonal view according FIG. 1.
